UNITED STATES PATENT OFFICE.

VICTOR E. LA VANWAY AND OLIVE L. LA VANWAY, OF TACOMA, WASHINGTON,
ASSIGNORS OF ONE-HALF TO FRANK WAYNO, OF TACOMA, WASHINGTON.

DESIGN FOR A CHILD'S VELOCIPED.

55,865.

Specification for Design.

Patented July 20, 1920.

Application filed February 7, 1920. Serial No. 357,108. Term of patent 7 years.

To all whom it may concern:

Be it known that we, VICTOR E. LA VANWAY and OLIVE L. LA VANWAY, citizens of the United States, residing at Tacoma, in the county of Pierce, State of Washington, have invented a new, original, and ornamental Design for a Child's Velocipede, of which the following is a specification, reference being had to the accompanying drawing, forming part thereof.

Figure 1 is a top plan view of a child's vehicle showing our new design; Fig. 2 is a side elevational view thereof; Fig. 3 is a front elevational view of the same.

What we claim, is—

The ornamental design for a child's velocipede, as shown.

VICTOR E. LA VANWAY.
OLIVE L. LA VANWAY.
